UNITED STATES PATENT OFFICE.

CHARLES KOEGEL, OF HOLYOKE, MASSACHUSETTS.

SLITTING-CUTTER FOR PAPER-MACHINES.

No. 852,964.

Specification of Letters Patent.

Patented May 7, 1907.

Application filed April 19, 1904. Serial No. 203,892.

To all whom it may concern:

Be it known that I, CHARLES KOEGEL, a citizen of the United States of America, residing at Holyoke, in the county of Hampden and State of Massachusetts, have invented new and useful Improvements in Slitting-Cutters for Paper-Machines, of which the following is a specification.

This invention relates to rotary slitting cutters such as are used on paper machines to cut the web of paper into strips of the desired width. It has heretofore been customary to make these rotary slitting cutters slightly concaved for the purpose of providing a good cutting edge at the point of contact between the upper and under slitters, and the manner of making these cutters has been to concave them and finish them up true while in an annealed state, and then harden them: but it has been found extremely difficult, if not impossible, to harden the concaved cutters and have them come out true, they at times being so badly sprung as to render them unfit for use, and even under most favorable circumstances the cutting edge will be wavy, this condition resulting in the production of a ragged edge, in spots, on the paper being cut. The only manner of overcoming the defects in the cutter, arising from an uneven cutting edge thereon, has been to press the cutting edges together much harder than is necessary to cause them to operate properly, if the edge were true, and this has the disadvantage of causing undue wear.

The object of the present invention is to provide a slitting cutter which may be finished and hardened flat, and in the provision of means to mount the same on a hub so constructed that in securing the cutter to the latter it may be concaved as much or as little as desired, within certain limits, the cutter and its hub constituting practically one piece which may be shifted from the paper machine to the arbor of a grinding machine without disturbing the adjustment of the support on the paper machine and without disturbing the adjustment of the cutter relative to its hub. In other words, the cutter may be ground on the same axis as that on which it rotates in the paper machine.

The invention is clearly illustrated in the drawings accompanying this application, in which,—Figure 1 is a perspective view of a fixture on which the upper cutter is supported, the latter being shown in position on said

fixture, and a portion of the lower cutter being also shown. Fig. 2 is a sectional elevation of the upper cutter and the hub on which it is mounted, the latter being shown 60 in position on the stud on which it rotates. Fig. 3 is a perspective view of a cap forming part of the means to secure the upper cutter on the stud on which it is mounted.

The fixture shown in Fig. 1 is that in common use, and it consists in a split collar *a* fitted on a suitable shaft, the collar having a lug *b* on one side thereof through which a vertical post *c* extends, and which is vertically and rotatably adjustable therein. In 65 the lower end of this post *c* is a stud *e* secured therein in any suitable manner. This post and the stud *e* are made adjustable in the manner described to make it possible to adjust the overlapping cutting edges of the slitting cutters *f* and *g*, one relative to the other,—*f* being the upper, and *g* the lower cutter. The latter may be fixedly secured in any desired position on the shaft *h*, but the upper one *f* is so mounted on the stud *e* as to be 75 spring-pressed toward the lower one.

Referring now to Fig. 2, particularly, the fixture on which the cutter *f* is mounted and on which it is concaved has been, and will hereafter be, referred to generically as a hub, 80 and it consists in a long sleeve *j*, one end of which is threaded to receive the nut *k*; and between this threaded end and the opposite end a circular flange *m* is located in the face of which, next to the nut *k*, there is turned an 85 annular depression *o*, that end of the sleeve opposite to that on which the nut *k* is located being turned down to provide a shoulder *p*; and over this turned-down end there is fitted a spiral spring *q* which normally extends beyond the end of the sleeve and has a bearing 90 against the shoulder *p*. The sleeve is bored out to fit the stud *e* on which it may rotate freely.

Over the end of the sleeve on which the spring *q* is located, the cap *r* (shown in Fig. 3) is fitted, the closed end of the cap being bored out to fit the stud *e*, and this closed end is provided with the oppositely located slots *t* therein. When the cap *r* is fitted over the end of the sleeve, the end of the stud *e* will project therethrough, said end being slotted and a locking latch *u* being pivotally mounted in the slot in such manner that it may be swung 105 out axially with the pin as shown in Fig. 2 in dotted lines, to permit the cap *r* to be fitted

over the end of the sleeve and then swung to a position at right angles to its dotted position, as shown, and fitted into the slots *t* in the flange *s* of the cap, thereby locking the cap to the stud *e* in a manner to hold the spring *q* under compression, when the edge of the cutter *f* bears against the edge of the cutter *g*.

On the inner face of the nut *k* there is turned a cylindrical flange *v* which fits closely the central perforation in the cutter, and serves to center the latter, relative to the sleeve, the nut having a bearing on the cutter outside or beyond this flange, as shown in said Fig. 2.

When the cutter is to be secured to its hub, it is first slipped over the threaded end of the sleeve *j*, the nut *k* being then screwed on to the sleeve and the flange *v* entered in the perforation through the cutter. The nut is then turned up as tightly as may be necessary to force in the center of the cutter, the outer edge of the flange *m* (which is of greater diameter than the nut *k*.) serving as a fulcrum.

The cutter is mounted and adjusted in the hub before the latter is secured on the stud *e*, and the adjustment of the parts is such that when so mounted and locked in position by the latch *u*, the edge of the cutter *f* will bear to a proper degree against the edge of the cutter *g*. It is customary in mounting these cutters to provide means to separate their cutting edges if, for any reason, certain of them are not to be used, a convenient way of effecting this separation being to mount a sliding bolt, as *w*, in the lower end of the post *e*, and in providing a cam surface *w*¹, on the opposite side of the post, against which surface the pin *w*² in the bolt bears, whereby when the bolt is rotated, the end thereof will be forced against the side of the cutter and push it on its stud *e* out of contact with the cutter *g*.

By means of the described construction, it is possible to manufacture the cutters far more economically than in the manner here-

tofore employed, and aside from this economy in manufacture, there is a further incidental saving due to the fact that none of the cutters are ruined in hardening; furthermore, the cutter having once been adjusted in its hub, and adjusted to the proper degree of concavity, it may be removed from the stud *e* at will without disturbing that adjustment. This is important in that it provides means for grinding the cutter on the same axis as that on which it rotates when in operation.

It will be seen that there is a tremendous advantage in forming a slitting cutter as a complete, uninterrupted disk or annulus which is punched out flat, tempered flat, and ground flat, and after having been dished or formed into cup-shape, by the devices herein set forth, it springs back into flat form as soon as released from the clamping devices and may be then reground to give it a new cutting edge, so that the entire cutting edge will lie in the same plane.

Having thus described my invention, what I claim and desire to secure by Letters Patent of the United States, is:—

1. A cutter or knife formed as a complete uninterrupted annulus having a single large central opening, and means for clamping said cutter or knife in working position and simultaneously dishing the cutter or knife.
2. A cutter or knife formed as a complete uninterrupted annulus having a single large central opening, a clamping member provided with a projection extending into said single central opening, a second clamping member, and means to move said clamping members toward each other to clamp and dish the said cutter or knife.

CHARLES KOEGEL.
